UNITED STATES PATENT OFFICE.

RAYMOND B. PRICE, OF NEW YORK, N. Y.

PROCESS OF TREATING PLASTIC MATERIALS.

1,152,837.

Specification of Letters Patent.

Patented Sept. 7, 1915.

No Drawing.

Application filed March 8, 1913. Serial No. 753,126.

To all whom it may concern:

Be it known that I, RAYMOND B. PRICE, a citizen of the United States, residing in the borough of Manhattan, city of New York, 5 State of New York, have invented new and useful Improvements in Processes of Treating Plastic Materials, of which the following is a specification.

My invention relates to the treatment of 10 plastic material, such as rubber and the like, and more particularly to the setting or vulcanizing of the same, and has for its object to provide certain improvements in the process of treating the same as will be herein- 15 after more specifically described and claimed.

More specifically, my improvement consists in treating the article or material, whether in assembled form, like a boot or 20 shoe, or in bulk, first, to a preliminary heating above the setting or vulcanizing temperature, and either under pressure or without pressure, or in a vacuum, said pressure or vacuum being of any desired degree, and 25 then setting or vulcanizing the same by any desired method whatsoever. And I contemplate a preliminary warming of the material being treated, without any pressure, and with or without the application thereto of a 30 vacuum, preliminary to said higher temperature, and which may be intermittent with said higher temperature, or may follow it, if desired. In fact, I contemplate the application of either or both of these described 35 heating or warming steps, as well as the subsequent setting or vulcanizing step under any conditions of pressure or vacuum and at any desired speed.

By the setting or vulcanizing temperature 40 I mean that temperature at which the article or material begins practically to set or vulcanize, which in the case of rubber is at approximately the melting point of sulfur. This preliminary heating of the article or 45 material is what may be termed a warming-up process, and any setting or vulcanization caused thereby will be merely superficial. Excellent results can be obtained by disposing the article or material to be treated in a 50 heater suitably warmed and then admitting

a pre-heated gas, and for this purpose I may employ any desired gas, inert or not, or steam. The material or article so pre-heated is then subjected to the setting or vulcanizing heat, which may be by means of steam, 55 air or other gas or vapor under pressure, or any of the same at atmosphere. Where steam is used it may be preferable that the air temperature exceed that of the maximum temperature of the steam admitted, in 60 order to insure more thoroughly against condensation. And it will be understood with respect to all of the steps hereinbefore described that the pressure or vacuum may be varied at will during the operation, and 65 that the preliminary and setting or vulcanizing heats may be also varied at will during their respective operations.

In carrying out my improved process I contemplate either the use of separate heaters or vulcanizers, one for the pre-heating and one for the setting or vulcanizing, or the carrying out of both steps of the process in the same heater.

Having thus described my invention, what 75 I claim as new and desire to secure by Letters Patent is:

1. The process of treating settable material or articles, which consists in first subjecting the same to a preliminary warming, 80 at or under atmospheric pressure, then to a pre-heating at a temperature above the setting temperature, and then subjecting them to the setting operation.

2. The process of treating settable materials or articles, which consists in first subjecting the same to a preliminary warming, 85 at or under atmospheric pressure, then to a pre-heating at a temperature above the setting temperature and at a controllable pressure above, at or below atmosphere, and then subjecting them to the setting operation.

3. The process of vulcanizing rubber, which consists in first subjecting the same to a preliminary warming, at or under atmospheric pressure, then to a pre-heating at a temperature above the vulcanizing temperature, and then vulcanizing the same.

4. The process of vulcanizing rubber, which consists in first subjecting the same to 100

a preliminary warming, at or under atmospheric pressure, then to a pre-heating at a temperature above the vulcanizing temperature and at a controllable pressure above, at 5 or below atmosphere, and then vulcanizing the same.

In testimony whereof, I have hereunto set

my hand in the presence of two subscribing witnesses.

RAYMOND B. PRICE.

Witnesses:

CHARLOTTE M. SCHULE,
MAY V. SMITH.
